(57) **CLAIM**

The ornamental design for a varmint repellent strip, as shown and described.

DESCRIPTION

FIG. 1 is a front perspective view of the varmint repellent strip of the invention in place on a deer feeder to show the general environment of the invention, the feeder being shown in phantom lines and forming no part of the claimed design;

FIG. 2 is an enlarged front perspective view, being shown broken away to indicate indeterminate length;

FIG. 3 is a front elevation view thereof;

FIG. 4 is a right side elevation view thereof;

FIG. 5 is a left side elevation view thereof;

FIG. 6 is a rear elevation view thereof; and,

FIG. 7 is a top plan view, with the bottom plan view being a mirror image thereof.
